(57) **CLAIM**

The ornamental design for a battery pack for uninterruptible power supply, as shown and described.

DESCRIPTION

FIG. 1 is a front view of one embodiment of a battery pack for uninterruptible power supply, as viewed from the front, embodying our new design;

FIG. 2 is a rear view thereof;

FIG. 3 is a left side view thereof;

FIG. 4 is a right side view thereof;

FIG. 5 is a top plan view thereof;

FIG. 6 is a bottom view thereof; and,

FIG. 7 is a perspective view thereof.
